APPARATUS FOR RECONDITIONING METAL SURFACES

Herbert H. Moss, Brooklyn, and Joseph E. Dawson, Niagara Falls, N. Y., assignors to The Linde Air Products Company, a corporation of Ohio

Original application November 29, 1933, Serial No. 700,188, now Patent No. 2,194,909, dated March 26, 1940. Divided and this application June 17, 1939, Serial No. 279,634

3 Claims. (Cl. 266—5)

This invention relates to apparatus for eliminating certain objectionable metallurgical changes which are produced in high-carbon and alloy steels when they are severed by means of high-temperature heating and oxidizing agents, e. g., the oxy-acetylene cutting flame. This application is a division of our copending application, Serial No. 700,188, filed November 29, 1933, now Patent No. 2,194,909, issued March 26, 1940.

As a result of flame-cutting or similar high-temperature operations, surfaces and surface edges of certain grades of steel are hardened and/or otherwise altered to an extent that renders the flame-cut surfaces and surface edges too hard or otherwise unsuited to withstand the commercial operations of fabrication and erection, and subsequent service in industry and commerce. This hardening or other change in the desirable physical properties of these steels invites the formation of fine hair cracks, notches, or ruptures in the steel at the cut surfaces and surface edges, which serve as roots for immediate or subsequent cracking. The presence of this characteristic is particularly marked in those grades of steel (such as carbon steels containing above about 0.35% carbon, the structural steels and some alloy steels containing nickel, chromium, manganese or vanadium) of which the compositions are such as to impart to them the property of air hardening when they are heated beyond their recrystallization temperature and allowed to cool rapidly in air—conditions which are approached or duplicated in the severing of such metals by the ordinary practices of flame cutting. Furthermore, it is very difficult and expensive to machine such hardened surfaces by customary machine tools, as for example, in removing the hardened metal or in milling the ends of structural steel members which have been rough sized by flame cutting.

Accordingly, the principal object of this invention is to provide improved apparatus for reconditioning or restoring the metallurgical structure of such severed steel surfaces to re-establish therein the desirable properties of the metal so that it may be used directly for structural purposes without machining off hardened edges and without the customary furnace heat treatment of the entire piece of steel.

The above and other objects, as well as the

novel features of this invention, will become more apparent from the following description considered in connection with the accompanying drawing, in which:

5 Figs. 1, 2 and 3 are respectively side, end, and plan views of a machine embodying this invention; and

Fig. 4 is a plan view showing an alternative form of the apparatus.

Ordinarily when the oxyacetylene cutting flame (consisting of one or more high-temperature gaseous heating jets and a gaseous oxidizing jet) progressively severs metal such as a plate of high-carbon steel or structural steel, the metal at the point of cutting attains a very high temperature which drops very rapidly at the moment the cutting flame leaves each successive point. This rapid temperature drop is due to the chilling or quenching effect of the adjacent air and the adjoining mass of metal, and results in decided and objectionable changes in the physical properties of the metal along the cut or exposed surfaces, as set forth above.

Generally speaking, the improved apparatus 15 may be used to provide what may be termed "localized heat treatment" by the application of one or more sources of local high-temperature heat directly to such flame-cut surfaces and the metal adjoining the same.

20 According to the present invention one or more oxyacetylene or similar high-temperature heating flames are progressively applied directly to successive portions of the thermally-affected edge formed during the flame cutting, after the cut has been completed but preferably before such edge or surface completely cools. The sources or units of localized high temperature heat or flames are of sufficient number and intensity to reheat the newly formed edges to a predetermined degree; e. g., above the critical 25 temperature of the metal being treated. Additional heating flames or units, preferably of lower intensity or temperature, are applied to the edge following the application of the first

30 reheating flame or bank of flames. The second bank of flames preferably consists of one or more high-temperature oxy-fuel gas flames applied progressively to the reheated cut edge, the flames 35 preferably being so regulated that the reheated edge cools at such a slow rate that the metal-

urgical structure of the edge portion of the metal is substantially improved. The cooling of the reheated surface thus may be retarded sufficiently to anneal the metal; that is to say, the metal, having been reheated above its critical temperature, has additional localized heat applied thereto less rapidly than the heat is dissipated therefrom (whereby it is permitted to cool at such a slow rate as to result in a desirable softening of the steel).

The accompanying drawing illustrates a machine operating according to the procedure just described. It is preferred to employ two or more separate multiple-nozzle oxyacetylene blowpipes or heating heads A and B to perform the surface reconditioning operation along the newly-formed and hardened edges of flame-cut or similar thermally-affected steel, as represented by the workpiece W. The multiple-jet heating heads A and B are suitably mounted on a support S which may be adjusted vertically and horizontally with respect to the work W and which is movable lengthwise of the edge of the work so that the jets from the blowpipes may be made to traverse the entire cut surface or newly-formed edge II of the work.

The heating head A is desirably provided with multiple nozzles, preferably extending horizontally to reheat the edge II of the metal to a desired maximum temperature. By adapting the second heating head B to confront a relatively long area of the edge of the metal, the nozzles thereof may be made to apply heat to the surface in such measure as to retard the cooling process.

For the purpose of moving the support S and the heads A and B relatively to the work, the support S may be mounted on a carriage E which is adapted to roll on tracks or rails 12 adjacent to and extending lengthwise of the edge of the workpiece W. The support S desirably comprises adjustment means such as a yoke 13 having a rack 14, and a base 15 within which the yoke 13 may slide vertically when the rack is moved by a pinion 16 and a hand-operated wheel 17. The base 15 is laterally adjustable on the chassis of the carriage S, being dovetailed on a slide 18, and the entire support S is movable transversely of the carriage E by a handwheel and screw 19. When the workpiece W is resting on an elevated support or table alongside of the rails 12, as in general practice, the heating heads A and B may be adjusted vertically and spaced horizontally by the devices 17 and 19, respectively, so as to properly position the blowpipes to operate on the work edge II. The carriage E may be propelled along the rails by a motor M and speed-reducing gearing 20, and a rheostat 21 may be provided to control the amount of current passing through the motor-field winding and thus regulate the motor speed and the rate of movement of the carriage E and the heating heads with respect to the workpiece W.

In utilizing a device constructed in accordance with this invention, the metal along the edge II is first reheated or raised to a predetermined degree above the critical temperature of the metal being treated, after which the reheated edge is exposed to the action of and influenced by one or more following sources of local high-temperature heat to moderate the hardness of the metal or to restore the properties it had before being exposed to the flame-cutting or similar operation. The first reheating head A supplies the intense heat necessary to raise the temperature to

the desired degree while the following head or heads B supply less intense heat, either to insure gradual cooling in such a manner as to prevent hardening of the reheated surface, or to

5 modify the hardness after the edges have partially cooled, as by providing localized tempering heat. The flames of the heating heads preferably are applied perpendicularly to and uniformly over the successive portions of the surface II.

10 In order to secure a uniform metallurgical structure of the cut edge II, it is important that the successive parts of the cut surface be reheated properly and uniformly to the correct elevated temperature for a brief time interval before subjecting them to the delayed cooling which follows immediately. Accordingly, in the herein-disclosed apparatus, the relative progressive movement between the work and the blowpipes relatively to each other may be varied, as by in-

15 creasing or decreasing the motor speed as the reheated condition of the cut edge varies from a predetermined standard. The operator of the apparatus may watch the reheating flame and the color of the reheated surface immediately after it leaves the reheating flame, and may operate the rheostat 21 to increase or decrease the motor speed, as required, to maintain the correct reheating condition.

20 As the temperature relationships are critical, it may be difficult to obtain precise results by means of such manual control, because of the personal error introduced by the operator as a result of misjudgment, neglect, or fatigue. The correct reheating condition may be precisely

25 maintained at every point along the surface II by mechanism which is automatically responsive to variations in the thermal condition of, or in the radiant energy emitted by the reheated surface. As shown in Fig. 1 of the drawing, this result may be accomplished by means of a photoelectric cell C which is focused on the reheated surface at a point immediately following the reheating head A. The cell C is connected by an appropriate electrical circuit to a reversible electric motor 22 that is arranged to operate the rheostat 21 to increase or decrease the resistance in the field or armature circuit of the driving motor M and thereby vary its speed, as required.

30 Briefly, whenever the light rays or radiant energy emitted by the successively reheated parts of the surface II vary above or below a predetermined normal condition (determined by the proper initial setting of the reheating flames and the speed of motor M when the reconditioning operation is started), a corresponding change is produced in the current flowing in the photocell circuit 23. The current increase or decrease is amplified in the amplifier 24 and transmitted to the coil 25 of a sensitive relay having a contactor 26 adapted to close the circuit of one or the other of two power relays 27 and 28. The respective power relays control the supply of current from the line L to the rheostat motor 22 and cause the latter and the worm gearing 29 to rotate either clockwise or counterclockwise and thus operate the rheostat 21 to either increase or decrease the driving speed of motor M, as required, instantaneously to correct any slight deviation from the proper reheating condition at every point along the surface II. Accordingly, with the photocell C focused on a narrow area of the edge II, for example, at a point between the heating heads A and B, and with the electrical circuits properly adjusted so that a predetermined correct reheating condition is provided, the photo-

cell control system maintains such condition at successive points along the surface 11 as the reconditioning operation progresses. The heating heads A and B may be provided with separate pairs of connections and valves 30 and 31 in order that suitable gases, such as oxygen and acetylene, from supply conduits 32 and 33, respectively, may be delivered to the head B at a lower pressure than at the first reheating head A. The temperature produced by the jets from the nozzles of the after-heating blowpipe B may be regulated and the system adjusted within substantially wide limits to produce the desired rate of slow cooling, or secondary heat-treatment, as required.

By applying localized heat to a relatively long zone or area along the path of travel, the successive portions of the metal to be conditioned are heated to above the critical range, as by the head A, and the portions are then allowed to cool slowly, as by exposure to the less intense heat from head B. The rate of travel and the intensity of the heat from the respective sources are correlated factors that may be coordinated to suit the requirements of the particular metal undergoing treatment. The nature of the heat-treatment to be applied is affected by such factors as the size of the metal object, its composition, the hardness of the exposed surface, and the degree of ductility desired in the reconditioned metal. Generally speaking, the successive portions are quickly raised to an annealing temperature, maintained briefly at that temperature by the successive jets of head A to obtain full penetration of the heat to the affected parts, and then are exposed to flames of graduated intensity to allow delayed cooling, preferably at a rate controlled by the photocell C. As a result the metal may be subjected to an action closely resembling a furnace annealing treatment, but wherein only a relatively small but elongated edge or surface portion of the entire metal body is heated, with consequent advantages in saving of time and heat. The apparatus, being of a portable nature, is readily available for operation both in the field and shop, and minimizes handling of the metal.

The bank or banks of flames following the head A in tandem may be of uniform capacity, in which case the successive heating heads may be adapted to apply flames of progressively lower intensity by restricting the flow of the combustible mixture at the respective valves 30 and 31 or by blanking off trailing nozzles of the blowpipe B or by any other convenient method. An alternative means for applying heat of gradually lower intensity along an elongated zone on the path of travel is disclosed in Fig. 4. A first heating head A' provides the necessary localized heat to raise the temperature to or above the annealing range and the following heating heads may be of progressively lower capacity, that is, by utilizing fewer nozzles, or smaller nozzles requiring less of the combustible mixture. In Fig. 4, a second heating head B' of lower capacity is shown, wherein a bank of nozzles 40 are progressively shorter with discharge orifices at successively greater distance from the leading end of the bank and from the work, whereby the heat delivered by the blowpipe B' may be tapered off in intensity. A photocell unit C may be located between the heads A' and B' to control the rate of travel as previously described.

While it is preferable to employ gaseous heat-

ing means to recondition flame-cut metal surfaces, it will be evident that electrical heating means such as electric arcs may be used in some instances to reheat such surfaces, or a combination of the gaseous and electrical heating media may be used, one for reheating and the other for retarding cooling. While the herein disclosed invention is especially applicable to the reconditioning of air-hardening grades of structural steel, it is obvious that the principles of this invention may also be employed in treating and reconditioning surfaces of other metals such as have been exposed and thermally affected by an oxyacetylene cutting flame or an equivalent high-temperature severing procedure. Various other changes may be made in the details of the apparatus hereby disclosed without departing from the invention or sacrificing any of its important advantages.

20 We claim:

1. Apparatus for locally reconditioning surface portions of a hardened steel body, said apparatus comprising, in combination, a carriage movable relatively to said body along a predetermined path; a first blowpipe head on said carriage having means adapted to project flames locally against successive zones of said surface portions along said path, said flames being adapted to raise the temperature of said zones to above the critical temperature; a second blowpipe head on said carriage in spaced tandem relation to and of lower capacity than said first blowpipe head, said second blowpipe head having means adapted to project flames of graduated intensity 25 locally against said successive zones to thereby reheat said zones moderately after said zones have cooled to a point appreciably below said critical temperature; a motor adapted to propel said carriage at predetermined speeds; and a photocell disposed on said carriage in circuit with said motor and being responsive to radiant energy emitted by such heated zones to control the speed of said motor and thereby the rate of travel of said respective blowpipe heads 30 to maintain a uniform reconditioning action by said heads along the entire length of said path.

2. Apparatus for locally reconditioning surface portions of a hardened steel body, said apparatus comprising, in combination, a carriage movable relatively to said body along a predetermined path; a first blowpipe head on said carriage having means adapted to project flames locally against successive zones of said surface portions along said path, said flames being 35 adapted to raise the temperature of said zones to above the critical temperature; a second blowpipe head on said carriage in spaced tandem relation to and of lower capacity than said first blowpipe head, said second blowpipe head comprising flame-projecting means adapted to apply progressively less heat at respectively greater distances from said first head locally against said successive zones to thereby reheat said zones moderately and retard the cooling thereof; and 40 a motor adapted to propel said carriage and thereby said heads at a predetermined speed along said path.

3. In an apparatus for locally reconditioning surface portions of a hardened steel body, the combination comprising, a carriage movable relatively to said body along a predetermined path; a motor for propelling said carriage at predetermined speeds; and blowpipe means mounted on said carriage having discharge portions arranged 45 in tandem and adapted to project flames locally

against successive zones of said surface portions along said path, said blowpipe means being provided with leading discharge orifices adapted to project flames of relatively high heating intensity for heating the forward portion of said successive zones to above the critical range, said blowpipe means being provided with trailing dis-

charge orifices adapted to apply progressively less heat at successively greater distances from said leading discharge orifices for retarding the cooling of the portions of said zones heated by 5 said leading discharge orifices.
